Primary Examiner — Robert A Delehanty

(74) Attorney, Agent, or Firm — Banner & Witcoff, Ltd.

(57) **CLAIM**

The ornamental design for a faucet spray head, as shown and described.

DESCRIPTION

FIG. 1 is a front perspective view of a faucet spray head showing my new design;

FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a cross-sectional view taken through line 7-7 of FIG. 3.

The broken line showing of the remainder represents unclaimed areas and forms no part of the claimed design.

1 Claim, 6 Drawing Sheets
